US0D1066124S

(12) **United States Design Patent** (10) **Patent No.:** **US D1,066,124 S**
(45) **Date of Patent:** **** Mar. 11, 2025**

(54) **VEHICLE**

(71) Applicants: **Zhejiang ZEEKR Automobile Research & Development Co., Ltd., Ningbo (CN); Zhejiang Geely Holding Group Co., Ltd., Hangzhou (CN)**

(72) Inventor: **Asok George**, Gothenburg (SE)

(73) Assignees: **Zhejiang ZEEKR Automobile Research & Dev. Co., Ltd., Ningbo (CN); Zhejiang Geely Holding Group Co., Ltd., Hangzhou (CN)**

(**) Term: **15 Years**

(21) Appl. No.: **29/834,769**

(22) Filed: **Apr. 14, 2022**

(51) LOC (15) Cl. **12-08**

(52) U.S. Cl.

USPC **D12/91**

(57) **CLAIM**

The ornamental design for a vehicle, as shown and described.

DESCRIPTION

FIG. 1 is a rear, right perspective view of a vehicle showing my new design;

FIG. 2 is a left side view thereof;

FIG. 3 is a right side view thereof;

FIG. 4 is a top view thereof;

FIG. 5 is a front view thereof; and,

FIG. 6 is a rear view thereof.

The broken lines, surrounding the ghosted or low contrasted areas, in the drawings illustrate portions of the vehicle that form no part of the claimed design.

1 Claim, 5 Drawing Sheets
